UNITED STATES PATENT OFFICE.

EMANUEL RAU, OF NEW YORK, N. Y., ASSIGNOR TO HARRY TORCHIANI, OF SAME PLACE.

MACHINE FOR PITCHING BARRELS.

SPECIFICATION forming part of Letters Patent No. 617,185, dated January 3, 1899.

Application filed July 1, 1898. Serial No. 684,922. (No model.)

To all whom it may concern:

Be it known that I, EMANUEL RAU, a citizen of the United States, residing at New York, in the borough of Manhattan and State of 5 New York, have invented certain new and useful Improvements in Machines for Pitching Barrels, of which the following is a specification.

This invention has reference to certain improvements in the machines for pitching barrels for which Letters Patent of the United States were granted heretofore to Maximilian Guethler, No. 573,818, dated December 22, 1896, whereby said machine is rendered more 15 reliable and effective in operation and brought more fully within the control of the attendant; and the invention consists of a machine for pitching barrels which comprises a kettle, means for heating the same, a reservoir suspended within said kettle, a valve for supplying melted pitch from the kettle to the reservoir, a pipe for supplying compressed air to said reservoir, a valve for opening or closing said compressed-air pipe, and 25 means for simultaneously operating the pitch-supply valve and the compressed-air valve.

The invention consists, further, of the connection, with the valve for receiving melted pitch from the kettle surrounding the same, 30 of a discharge-pipe leading from the tank into the keg or barrel to be pitched, said pipe being supported in suitable bearings and provided with wings or blades at its lower end and with openings, so as to rotate the discharge-pipe while forcing the melted pitch through the same.

The invention consists, further, of certain details of construction and combinations of parts, which will be fully described hereinafter, and finally pointed out in the claims.

In the accompanying drawings, Figure 1 represents a plan view of my improved machine for pitching barrels. Fig. 2 is a vertical transverse section of the same on line 2 2, Fig. 45 1. Fig. 3 is a vertical longitudinal section on line 3 3, Fig. 1. Fig. 4 is also a vertical longitudinal section of the machine on line 4 4, Fig. 1, drawn on a larger scale. Fig. 5 is a horizontal section on line 5 5, Fig. 4. Fig. 6 is 50 a detail horizontal section on line 6^b 6^b, Fig. 4, drawn on a still larger scale and showing

the relative position of the air-valves of the compressed-air pipes and the pitch-supply valve in their positions of rest; and Figs. 6^a and 6^b are diagrams showing the positions of the 55 pitch-supply valve and air-valves when alternately pitching barrels on opposite sides of the machine.

Similar letters of reference indicate corresponding parts.

Referring to the drawings, A represents a kettle for melting pitch, which kettle is supported in a suitable furnace, by which the same is heated. The furnace B may be of any approved construction. The kettle A is provided with a cover A', on which are arranged two or more supports C for the kegs or barrels to be pitched. Within the kettle is suspended by suitable bracket-hangers d d a closed tank or reservoir D, which is divided by a central partition D' into two compartments D², so that one barrel at a time can be supplied with pitch from each of the compartments.

In the drawings the pitching-machine is constructed for pitching two barrels; but it 75 is obvious that it can also be arranged for pitching four or more barrels, in which case the reservoir is divided by an additional partition at right angles to the partition D' into four compartments D². The apparatus may 80 also be used for pitching a single keg, in which case a reservoir with a single compartment is used. Within the reservoir D is arranged an upright valve-cylinder E, which is provided with openings e at its lower part, one 85 for each compartment D². The cylinder E is closed at its upper end and open at its lower end and attached to the bottom of the reservoir D. In the cylinder E is arranged a hollow valve E', which is provided with a 90 stem or spindle E², that extends through a stuffing-box b on the cover. The hollow valve E' is provided with an opening e', which registers with one of the openings e of the cylinder E, according as the valve is turned on 95 its axis in one or the opposite direction. The hollow valve E' is connected at its lower open end with a supply-pipe E³ for the melted pitch, which is supported by straps e³ on the bottom of the reservoir D and provided at 100 its upwardly-bent portion with a strainer E⁴, so that no coarse impurities can enter with

the melted pitch through the supply-pipe E³ to the reservoir D.

- My improved pitching-machine is operated by the medium of compressed air, by which 5 a suitable quantity of the hot pitch, which has been permitted to enter into one of the compartments D², is forced from the same into the keg or barrel which is to be coated with pitch at its inner surface. For this purpose a compressed-air pipe F is connected with the top of each compartment D², the compressed-air pipe being formed of a horizontal portion that is connected with a tank containing compressed air and with vertical 10 portions F', which pass through the cover A'. In the vertical portion of each compressed-air pipe F' is arranged a hollow air-valve f, having a port f', by which the compressed-air pipe can be placed in connection with the 15 compartment D². The air-valve f is made in the nature of a three-way valve—that is to say, its port f' can be placed either in communication with the compressed-air pipe F or with either one of two air-outlets f² f³ on the casing 20 of the air-valve f. When the air-valve f is in communication with the compressed-air pipe, the compressed air is conducted into the compartment D² after the same has been filled with 25 melted pitch, while in the other position the compartment D² is connected with one of the air-outlets f² or f³, so that the compressed air in the same can pass to the outside and atmospheric pressure be established at the interior of the compartment D². The spindle 30 of the air-valve f is provided with a gear-wheel g, which meshes with a gear-wheel g' on the stem or spindle E² of the valve E E', by which the melted pitch is supplied to the compartments D². To the upper end of the 35 stem or spindle E² is applied a handle H. When the handle H is turned in either direction, the pitch-supply valve and the air-valves are simultaneously turned so as to be placed into the proper positions for supplying 40 pitch and then compressed air to each compartment. The lower part of each compartment D² is connected by a short pipe g⁰ with a cylindrical casing G', which is provided 45 with a suitable step-bearing for the lower end 50 of a discharge-pipe G, that is adapted to turn in a stuffing-box at the upper part of the casing G' and in a neck-bearing in the cover A'. The discharge-pipe G extends to a sufficient height above the cover A' so as to bring the 55 perforated nozzle g¹ at its end in such a position in the barrel, placed on the support C, that the melted pitch is distributed uniformly in different directions in the barrel. The lower end of the discharge-pipe G is provided 60 with wings or paddles g², which form a kind of propeller-wheel, and with openings g³, through which the pitch is forced into the discharge-pipe while the same is rotated. The pressure of the melted pitch on the paddles in its passage to the openings of the discharge-pipe is sufficient to produce the rotation of the same. By the rotation of the dis-

charge-pipe G the pitch is distributed in a more effective manner on the interior of the barrel, so that thereby the pitching operation 7c is accomplished in a better and quicker manner. The surplus pitch is returned through the bung-hole of the barrel onto the cover within the support C and is then conducted back into the kettle through openings o in 75 the cover of the same, as shown in Fig. 1.

The products of combustion from the fuel burned in the furnace are conducted through a suitable smoke-stack to the atmosphere, while the vapors formed in the pitch-kettle 8c are conducted off through a suitable pipe, as shown in Figs. 1 and 3.

My improved pitching-machine is operated as follows: The pitch is charged into the kettle through an opening and hinged lid A² of the 85 cover A. After the pitch is melted a barrel is placed on each of the supports on the cover of the kettle. The operating-handle H is then in a position of rest—that is to say, in a position intermediately between the two air-valves, as shown in Figs. 1, 2, and 6. The compressed-air pipes are by their air-valves shut off from the compartments D², while the ports f' are in register with the outlets f², so that both compartments are under atmospheric pressure. In this position of the air-valves the pitch-supply valve E' is placed with its opening e' intermediately between the inlet-openings e of the valve-cylinder E, so that both compartments are shut off from 90 the kettle and no pitch can pass into either of them. This is the position of the valves when the machine is not in use. When the machine is to be used for pitching, the handle H is turned over to one side—say toward 95 the right—so that the port of the left-hand air-valve is placed in communication with the outlet f³, the opening in the pitch-supply valve E' in communication with the left-hand compartment D², and the port of the right-hand air-valve connected with the compressed-air pipe, as shown in Fig. 6^b. In this position of the valves the pitch in the right-hand compartment is discharged into the barrel to be pitched, while the left-hand compartment 100 is simultaneously filled with pitch under atmospheric pressure. The handle H is then turned over to the left, so as to be above the left-hand air-valve f. This motion brings the right-hand air-valve and its compartments 105 D² in communication with the atmosphere, the pitch-supply valve in communication with the right-hand compartment D², so that the latter can be filled with pitch from the kettle, and the left-hand air-valve in communication 110 with the compressed-air pipe F, as shown in Fig. 6^a, so that compressed air is supplied to the left-hand compartment and the melted pitch in the same forced through its discharge-pipe into the barrel on the support C. The 115 handle H is then turned over the right-hand air-valve, which motion places the valves back into the position shown in Fig. 6^b, so that the compressed air in the left-hand compartment 120

can be discharged while it is filling with melted pitch, while the melted pitch in the right-hand compartment is discharged into the barrel above the same. As soon as a barrel is pitched it is removed and a new one placed on the support. During the pitching operation the handle is always over the barrel that is pitched, which cannot be removed while the pitching action takes place, so that there is no possible chance of accident by hot pitch, for the reason that as soon as the handle is turned into the other position away from the barrel the discharge of pitch is immediately discontinued and transferred to the opposite discharge-pipe and the barrel on the same, over which the handle has been placed. When the pitching of one barrel takes place, the melted pitch flows into the compartment from which the compressed air has been shut off and which is then under atmospheric pressure, and so on alternately until all the barrels are pitched. By the arrangement of two three-way air-valves, which are jointly operated with the pitch-supply valve, the pitch-supply valve and the air-valves are always placed in the required position without any possibility of mistake by the attendant.

My improved pitching-machine has the advantage that the valves are under positive control, so that the alternate filling of the compartments with melted pitch and the discharge of the same by the pressure of compressed air on the same are produced. By the position of a single handle the attendant controls the regular and positive operation of the valves for the melted pitch and compressed air. As the compartments are connected with the atmosphere before being filled with pitch, the quick and reliable filling of the compartments from the kettle and the discharging of the pitch from the same into the barrels take place, while by the submerging of the compartments in the melted pitch the pitch is always kept in easily-flowing liquid condition and supplied to the barrels in this condition with but little loss of heat.

Having thus described my invention, I claim as new and desire to secure by Letters Patent—

50 1. The combination, with a pitch-kettle and means for heating the same, of a reservoir or tank submerged in the melted pitch in the kettle, a pipe for supplying the melted pitch from the kettle to said reservoir, a valve in said pitch-supply pipe, a compressed-air pipe leading into said reservoir, a three-way valve in said compressed-air pipe, a discharge-pipe, and means for positively operating the pitch-supply valve and the three-way valve so as to

charge the same, and reestablish atmospheric pressure in the reservoir, substantially as set forth.

55 2. The combination, with a pitch-kettle and means for heating the same, of a reservoir or tank submerged in the melted pitch in the kettle, a pipe for supplying melted pitch from the kettle to said reservoir, a valve in said pitch-supply pipe, a spindle for operating said valve, a compressed-air pipe leading into said reservoir, a three-way valve in said compressed-air pipe, a discharge-pipe, and means for simultaneously operating the spindle of the pitch-supply valve and the three-way valve so as to supply the reservoir with melted 75 pitch, discharge the same, and reestablish atmospheric pressure in the reservoir, substantially as set forth.

80 3. The combination, with a pitch-kettle and means for heating the same, of a closed reservoir submerged in the melted pitch in the kettle, a central partition in said reservoir dividing it into two compartments, a pitch-supply pipe connecting the reservoir with the kettle, a valve in said supply-pipe, a compressed-air pipe leading to each compartment, a three-way valve in each compressed-air pipe, and means for simultaneously turning the three-way valves with the pitch-supply valve, so that either compartment can be alternately placed in communication with the pitch-kettle, compressed-air pipe or the atmosphere, substantially as set forth.

85 4. The combination, with the pitch-kettle and means for heating the same, of a reservoir submerged in the melted pitch in the kettle, valved pipes for supplying alternately melted pitch or compressed air respectively to said reservoir, a discharge-pipe for said reservoir, and means for rotating said discharge-pipe while forcing the melted pitch through the same, substantially as set forth.

90 5. The combination, with a pitch-kettle and means for heating the same, of a reservoir submerged in the melted pitch in said kettle, valved pipes for supplying alternately melted pitch or compressed air to said reservoir, a discharge-pipe for said reservoir, a casing for the lower end of said discharge-pipe, step and neck bearings for said discharge-pipe, and 100 propeller-wings and openings on the lower part of the discharge-pipe within said casing, substantially as set forth.

105 In testimony that I claim the foregoing as my invention I have signed my name in presence of two subscribing witnesses.

110 EMANUEL RAU.
